UNITED STATES PATENT OFFICE.

ERVIN J. TAYLOR AND EDGAR TAYLOR, OF LYNCHBURG, OHIO.

PROCESS OF COLORABLY COATING PAPER.

No. 835,579.

Specification of Letters Patent.

Patented Nov. 13, 1906.

Application filed November 27, 1905. Serial No. 289,320.

To all whom it may concern:

Be it known that we, ERVIN J. TAYLOR and EDGAR TAYLOR, citizens of the United States, residing at Lynchburg, in the county of Highland and State of Ohio, have invented certain new and useful Improvements in Processes of Colorably Coating Paper, of which the following is a specification.

This invention has relation to machines and processes for colorably coating paper formed into rolls.

It is the object of the invention to provide a machine and process which shall be capable of colorably coating on one or both sides of a roll of paper with the same color on both sides, if both sides are coated, or with one color on one side and another color on the other side, if it is so desired.

The invention consists of the method or process of taking paper from a roll, and, if need be, stretching it to take out any wrinkles or marks of folding, and then passing the same around a large smooth steel roll where a rotary hair-brush applies the color from a color-box to one side of the paper, when the latter is moved in contact with a series of finishing-brushes which distribute the color thoroughly. The web is next subjected to a blast of hot air, passed in contact with a hot drying-roll, again subjected to a hot-air blast, and carried around another hot drying-roll which reverses its position and puts it in condition to have its opposite side treated in substantially the same manner.

The invention also consists in a machine for carrying out the foregoing process, as is clearly represented in the annexed drawings, forming a part of this specification, and in which—

Figure 1 is a sectional side elevation of so much of a machine embodying our invention as it is necessary to represent in order to fully disclose our improvements to those skilled in the art to which it relates. Fig. 2 is a diagram in plan of the main parts of the invention. Fig. 3 is a diagram of the front end, and Fig. 4 a diagram of the rear end, of the parts of the machine outlined in Fig. 2.

In the construction of means in which our improvements may be embodied and by which our process may be carried into effect we may employ flanged beams 1, of steel or other material, such as is commonly used in the making of the frames for the support of the operative devices of mill machinery, and in like manner construct journals, bearings,

and supports for the same. These instrumentalities vary in size and form as the requirements of the machine may vary—scarcely two orders to the machine-builder being the same as regards the particulars hereinbefore mentioned. It may, by the way, be said that these variations come within the scope of the skilled pattern-maker and machinist.

Of the essentials herein portrayed, A may indicate the roll of virgin paper B, reeled upon a suitable rotary mandrel a, from which it is drawn and passed about a rotary roll C, which is a simple idler. From the roll C the web passes to and about a steel roll D, which is quite smooth and forms a solid surface for the paper to be stretched upon, so that the color-brush E may distribute the color evenly thereon. Located in the color-box g is a brass roll F, which receives color from the said box and distributes it on the brush E, by which, as stated, it is applied to one side of the web, all as will be understood by an inspection of the left-hand end of the machine shown in Fig. 1.

An endless rubber apron b passes about the rolls H, arranged at the forward and rear ends of the machine, and the web B, of paper, after being treated to color by the brush E, as stated, passes from the roll D beneath the belt b and above the first reciprocating brush I, termed a "scrubbing-brush," which evenly distributes the color on the web. Next the web is met by the revolving bristle brush J, which serves merely in conjunction with the belt b to pull the paper along in the machine. The web next comes in contact successively with three reciprocating hair brushes K K K, the first of which shows a part of the supporting and tension means in place with it.

These means constitute no part of our invention, though they are connected with each reciprocating brush and are supplemented with additional means to secure their perfect operation and adjustment and are quite as ordinary and common in the art as the brushes themselves. The brushes K operate to smooth the coat on the paper and to operate with a little more energy than do the reciprocating brushes M M, which still further distribute the color-coating and smooths and polishes it, as it were. Next, before the web reaches the end of the machine, it is subjected to a hot blast of air, which impinges upon the coated side about as indicated by the arrow N. This blast of hot air may come from below and be supplied by a fan or blower and

has a tendency to dry the paper. Next the paper passes about a hollow steam or hot-air heated roll O, thence through a space P, where it is subjected to another hot blast of air, as indicated by the arrow, as at the point N, thence over a second heated roll Q, similar to the roll O, by which roll Q the position of the paper web is reversed, so that its coated side, which is now thoroughly dried, faces upward as it travels back toward the head of the machine, instead of facing downward, as it did below when traveling in the opposite direction and was treated as before described.

When the web B reaches the front of the machine, it passes about a roll R, similar to the roll D, and its uncoated side is treated to color and otherwise operated upon precisely as before as it is drawn to the rear end of the machine and leaves the upper rubber apron b, from whence it passes on an elevator of usual construction and arrangement, where it is dried and wound into a roll.

By the process and means described both sides of the web of paper may be thoroughly and evenly colored or enameled with the same or different colors and the work done in a most expeditious and economical manner. Whether the paper is colored alike on both sides or different on one side from that on the other, but one machine and one operation is required.

The steps in the process of drying are most efficient, while the application of the coating is thorough and in the end as smooth and even as is possible to have it. In reaching this end the brushes K, which act with energy, and the brushes L, which operate comparatively smoothly, play a very important part.

The arrangement of the rolls in and about the color-box may be varied within the limits of mechanical skill without varying our invention.

White enamel or liquid bronze may, it will be seen, be applied to the paper with facility and thoroughness equal to coloring-matter.

We claim—

1. The improvement in the art of enameling or coating paper which consists in first applying the coating to one side of the web, spreading or distributing it evenly thereon, drying the web by subjecting the same to a current of hot air, passing it about a heated surface, subjecting it to another current of hot air and then to a second heated surface, then applying a coating of the same or a different color or character to the other side of the web, spreading and distributing the coating thereon as before and drying it.

2. The improvement in the art of enameling or color-coating paper which consists in first applying the color-coating to one side of the web spreading or distributing it evenly thereon, and in the final spreading and distribution first operating with greater energy and latterly with less energy, drying the web by subjecting it to a blast of hot air, passing it in contact with a heated surface, subjecting it to another current of heated air and then to a second heated roll.

In testimony whereof we affix our signatures in presence of two witnesses.

ERVIN J. TAYLOR.
EDGAR TAYLOR.
